US00D723104S

(12) **United States Design Patent**
Cho et al.

(10) **Patent No.:** US D723,104 S
(45) **Date of Patent:** ** Feb. 24, 2015

(54) **PRODUCT IDENTIFICATION LABEL**

- (71) Applicants: **Han Yong Cho**, Yongin-si (KR); **Jae Wook Chun**, Seoul (KR); **Myung Ho Kang**, Seoul (KR)
- (72) Inventors: **Han Yong Cho**, Yongin-si (KR); **Jae Wook Chun**, Seoul (KR); **Myung Ho Kang**, Seoul (KR)

(**) Term: **14 Years**

(21) Appl. No.: **29/459,662**

(22) Filed: **Jul. 2, 2013**

(30) **Foreign Application Priority Data**

Jan. 2, 2013 (KR) 30-2013-0000166

(51) **LOC (10) Cl.** **19-08**
